CLAIM

The ornamental design for an earplug for a hearing aid, as shown and described.

DESCRIPTION

FIG. 1 is a perspective view of an earplug for a hearing aid showing my new design;

FIG. 2 is a plan view thereof;

FIG. 3 is an underside plan view thereof;

FIG. 4 is a front elevation of the earplug, the rear elevation being identical with FIG. 4;

FIG. 5 is a right-side elevation of the earplug, the left side elevation being identical with FIG. 5;

FIGS. 6 and 7 are, respectfully, transverse cross-sectional views through FIGS. 4 and 5, FIG. 6 being a section taken on line 6—6 in FIG. 4, and FIG. 7 being a section taken on the line 7—7 in FIG. 5; and,

FIG. 8 is a cross-sectional view taken along the line 6—6 of FIG. 4, the broken line showing of the hearing aid is for illustrative purposes only and form no part of the claimed design.
